SAFETY RAZOR

Samuel Trachtenberg, Cleveland, Ohio

Application February 14, 1933, Serial No. 656,660

10 Claims. (Cl. 30—12)

This invention relates to razors and particularly to safety razors. More particularly my invention relates to razors adapted to hold blades having a plurality of cutting edges which may be used successively to the end that the usefulness of the blade may be greatly prolonged before resharpening is required.

One of the primary objects of my invention is to provide a holder or handle for such blades which is simple in construction, easy and economical to manufacture and certain in its operation. A further object of my invention includes the provision of a razor blade having means formed with the blade whereby the blade itself is securely mounted on the holder and readily removed without any danger of cutting to the operator when he removes the blade. Further and incidental objects will appear more fully hereinafter.

For a complete conception of my invention reference may be had to the accompanying drawing and following description and while in said drawing I have only depicted the best mode in which I have contemplated embodying my invention, corresponding parts and mechanical equivalents are within the scope thereof. In said drawing,

Figure 1 is a view partly in elevation and partly in section of a complete razor and holder embodying my invention;

Figure 2 illustrates a face view of the razor and holder as viewed from the line 2—2 in the direction of the arrows;

Figure 3 is a transverse section taken as on the line 3—3 of Figure 2;

Figure 4 is a top plan view of a multi-sided blade for use with my improved holder;

Figure 5 is a transverse vertical section of the same taken on the line 5—5 of Figure 4;

Figure 6 illustrates a view partly in section and partly in elevation of a modified form of holder and blade; and

Figure 7 is a vertical section taken on the line 7—7 of Figure 6 showing optional means of tightening a blade.

Referring to the same parts throughout the several views by the same reference characters I designate a handle by the numeral 2. The handle 2 is preferably provided with a knurled surface 2b and a narrowed threaded portion 2a.

The threaded handle 2, a flat blade holder 3 and a razor blade 5 form the essential components of this invention. The flat holder 3 is preferably provided with an integrally formed boss 3e on the one side and has a bored central opening 3g

for purposes presently to be described. The boss 3e is also provided with angularly directed bores 3h and 3k. The former is tapped to receive the threaded portion 2a of the handle 2. Both the holes 3h and 3k at their lower end converge with the central hole 3g. The hole 3k is optionally provided and if used to give greater security is threaded to receive the set screw 6 preferably provided with a knurled head 6a.

The opposite face of the member 3 is provided preferably with a rib 3a forming the edge of the holder 3 on three sides. The other edge is provided with a guard 3b which makes one of the edges available for use in shaving. Pins 3c and rectangular bosses 3d are provided also on this face and fit the corresponding opening in the blade as presently to be described. The pins 3c and bosses 3d may be of any shape and disposed in any orderly manner but are preferably arranged in the manner shown in Figure 2.

A blade 5 for use with this form of holder is formed of a piece of steel having a plurality of cutting edges 5a. Circular and rectangular slots 5c and 5d respectively are punched in the blade, as well as a centrally located opening 5e into which a piece of tubing of brass or the like is fitted and secured by spot-welding, peening or similar methods. A piston like member 4, is slidably fitted within this tubing and its ends are riveted to form retaining flanges 4a. For use with the form of device shown in Figures 6 and 7 the blade stem 5b is provided with a threaded portion 5f.

In operation the central stem 5b of a blade is inserted in the opening 3g and the slotted portions 5c and 5d receive and encompass the pins 3c and 3d respectively, thus ensuring that the blade cannot move on the member 3 and become inoperative. To the end that only one of the cutting edges may be accessible the blade itself fits within the depressed portion formed by the ribs 3a previously described. In this manner there is no danger to the operator of being cut by any of the unused edges of the blade. When the members 3 and 5 are thus assembled the handle 2 is screwed tight and the razor is ready for use. If the member 3 is provided with the set screw 6 this is additionally tightened till its end frictionally engages the stem 5b.

In the modified form shown in Figures 6 and 7 a U-shaped member 3x is integrally formed with the boss 3. A collar 3 is slidably mounted in the top of the member 3x and is internally threaded to receive the tapped portion 5f on the stem 5b. An enlarged knurled flange 8a is provided at one

end of the collar while the other end is flanged or riveted as at 8b to prevent the collar from sliding out when the blade stem is removed. In this manner the blade may be tightened against 5 the face of the blade holder 3.

Special attention is directed to the shaft 4 which slides freely within the sleeve 5b. Shaft 4 and sleeve 5b may have any shape and since the sleeve is an integral part of the blade the 10 shaft 4 provides means for removing the blade without danger to the operator of being cut. If the razor handle is held ready for use the weight of the shaft 4 causes it to fall downwardly and assume the dotted positions shown in Figures 1, 15 5, 6 and 7 which if placed as shown in full line in these figures the weight of the shaft will cause to slide down. The turned edge 4a contiguous to the blade in its operative position presents no interference to the full and complete use of the 20 blade, since it is substantially flush with the face of the blade.

It will be apparent that the construction shown is simple and economical to manufacture and one in which parts may be eliminated if desired for 25 any reason by those skilled in the art to which my invention relates. Obviously, many modifications of the invention are possible as suggested by the drawing and specifications and included within the scope of the appended claims.

30 Having thus described my invention what I claim desire to secure by Letters Patent is:

1. A safety razor comprising a blade having an opening in its center, a sleeve registering with 35 said opening and secured to said blade, and a shaft slidably secured within said sleeve, a guard plate for said blade and a handle adapted to secure with itself said blade, sleeve and plate.

2. A safety razor comprising a blade having an opening in its center and a sleeve registering with 40 said opening and secured to said blade, and a shaft slidably secured within said sleeve, a guard plate for said blade having a boss on one side, a centrally located bore and an angularly disposed threaded bore joining said central bore, and a 45 handle threaded at one end adapted to secure with itself said blade, sleeve and plate.

3. A safety razor comprising a blade having an opening in its center and a sleeve registering with 50 said opening and secured to said blade, and a shaft slidably secured within said sleeve, a guard plate having means for holding said blade on one side and a boss on the other side, said boss having a centrally located bore and an angularly disposed threaded bore joining said central bore, and a handle threaded at one end and adapted 55 to secure with itself said blade, sleeve and plate.

4. A safety razor comprising a blade having 60 slots and a plurality of cutting edges, an opening in its center, a sleeve registering with said opening and integrally secured to said blade and a shaft slidably secured within said sleeve, a guard plate for said blade having teeth on one edge, a raised shoulder on the other edges, detent pins 65 registerable with said slots in one side and a boss on the other side, a centrally located bore and an angularly disposed threaded bore joining said central bore, and a handle threaded at one end and adapted to secure with itself said blade, sleeve and plate.

70 5. A safety razor comprising a blade having slots and a plurality of cutting edges, an opening in its center, a sleeve registering with said

opening and integrally secured to said blade, and a shaft slidably secured within said sleeve, a guard plate for said blade having teeth on one edge, a raised shoulder on the other edges, detent pins 5 registerable with said slots in one side and a boss on the other side, a centrally located bore and angularly disposed threaded bores joining said central bore, and a handle threaded at one end and adapted to secure with itself said blade, sleeve and plate.

6. A safety razor comprising a blade having slots and a plurality of cutting edges, an opening in its center, a sleeve registering with said opening and integrally secured to said blade, and a shaft slidably secured within said sleeve, a guard 15 plate for said blade having teeth on one edge, a raised shoulder on the other edges and detent pins registerable with said slots in one side and a boss on the other side, a centrally located bore and angularly disposed threaded bores joining 20 said central bore, a handle threaded at one end and adapted to secure with itself said blade, sleeve and plate by engagement with one of said threaded bores and a set screw engaging the other.

25 7. A safety razor comprising a square blade having regularly spaced slots and a plurality of cutting edges, an opening in its center, a sleeve registering with said opening and integrally secured to said blade, and a shaft slidably secured within said sleeve, a guard plate for said blade having teeth on one edge, a raised shoulder on the other edges and detent pins registerable with 30 said slots in any operable position in one side and a boss on the other side, a centrally located bore and angularly disposed threaded bores converging with said central bore, a handle threaded at one end and adapted to secure with itself said blade, sleeve and plate by engagement with one of said threaded bores and a set screw engaging 35 the other.

8. A safety razor comprising a blade having a plurality of cutting edges, an opening in its center, a sleeve registering with said opening and integrally secured to said blade, and a shaft slidably secured within said sleeve, a guard plate for 40 said blade having detent means in one side and a boss on the other side, a centrally located bore and an angularly disposed threaded bore joining said central bore, and a handle threaded at one 45 end and adapted to secure with itself said blade, sleeve and plate.

50 9. A safety razor comprising a blade having an opening, a sleeve registering with said opening, integrally secured at one end to said blade and threaded at the other, and a shaft slidably secured within said sleeve, a guard plate for 55 said blade, having a boss on one side with a U-shaped bearing formed on its top, a centrally located bore therein and an angularly disposed threaded bore joining said central bore, a nut rotatively secured within said bearing, axially aligned with said central bore and adapted for engaging the threaded end of said sleeve, and a handle threaded at one end and adapted to secure with itself said blade, sleeve and plate.

60 10. A razor blade having an opening, and a pin having flanges on its ends slidably but irre- 65 movably secured in said opening and longitudinally movable therein.
